APPARATUS FOR INTRODUCING AN ODOR-
ANT FLUID INTO A GAS LINERobert M. Hutchison and Frank Y. Hutchison,
Houston, Tex.

Application April 7, 1938, Serial No. 200,806

1 Claim. (Cl. 261—121)

This invention pertains to an apparatus and method for introducing a fluid, as for example an odorant, into a line in which another fluid, as for example natural gas, is flowing.

Previous attempts have been made to devise methods and apparatus for introducing an odorant into gas which is used for domestic or industrial purposes in order that a leak which otherwise might be dangerous will be evidenced by a disagreeable odor.

These prior attempts have not been successful for various reasons, as for example, their inability to handle the preferred types of odorants or by reason of the fact that the odorant is introduced at an uneven rate so as to result in a very strong odor at times and a scarcely noticeable odor at other times.

An object of this invention is to provide a method and apparatus by which the preferred commercial types of odorants may be introduced into a pipe line at the desired rate and in an economical manner and whereby the odorant will be introduced at a rate which is substantially proportional to the rate of flow of the gas in the line.

A further object of the invention is the provision of a method and apparatus which will require a minimum of attention on the part of an operator and which will not, under any circumstances, introduce a dangerously excessive amount of the odorant into the gas line.

Still another object of the invention is the provision of an apparatus having a storage tank for the odorant which can be refilled without interrupting odorization.

Other objects and advantages of the invention will be apparent from the accompanying description and drawings which describe and illustrate a preferred form of the invention for the purpose of exemplification.

In the drawings:

Figure 1 is a diagrammatic elevation of the apparatus showing its attachment to a pipe line;

Figure 2 is also an elevation of the apparatus taken at a right angle to the view shown in Figure 1;

Figure 3 is a detailed view, partly in section, of a portion of the apparatus shown in Figures 1 and 2, and

Figure 4 is a view, partly in section, taken on the line 4—4 of Figure 3.

The odorant which is used is a volatile liquid which will vaporize rapidly under ordinary atmospheric conditions of temperature and pressure and having ingredients which contribute a

strong odor to the vapor, as for example, sulfides and mercaptans. Most commercial odorizing liquids of this type consist principally of mixtures of hydrocarbons having a relatively wide boiling range, the various component hydrocarbons having different boiling points.

One example of such an odorant is "Calodorant" which is a refinery product consisting of a mixture of volatile hydrocarbon compounds together with ingredients which contribute a disagreeable odor. This particular product has a boiling range of 90° F. to 400° F. and in this respect, resembles gasoline. Because of its wide boiling range, it is very difficult to handle this odorant in the ordinary by-pass method of odorization. The lighter fractions of the liquid evaporate first, and as the heavier fractions become preponderant, the rate of evaporation decreases.

Furthermore, in the ordinary by-pass method, the composition and characteristics of the vapor emanated constantly change, as will be apparent from the following considerations. Each compound in the mixture exerts a partial pressure equal to the mol-fraction times its true vapor pressure if in a pure state under the same conditions of temperature and outside pressure; and therefore, at any definite temperature, each of the components exerts its own partial pressure dependent entirely upon its own mol-fraction in the combination.

If an inert gas is passed through or over such a mixture of compounds, the rate of evaporation of each individual compound is determined by its vapor pressure (when in a pure state) times the mol-fraction. Certain components will, therefore, vaporize more rapidly than the others, thus bringing about the lowering of these mol-fractions. This results in a proportional lowering of their rates of evaporation and also in an increase in the proportional rates of evaporation of the other components. As a result, the composition of the vapor progressively changes from a high proportion of the high vapor pressure components to a high proportion of the low vapor pressure components.

By the use of the method and apparatus hereinafter to be described, an odorant of this type may be evaporated into a confined stream of gas in such a manner that a vapor phase balance is obtained almost immediately and maintained as long as the apparatus is in operation. By vapor phase balance we mean a condition wherein the liquid odorant is vaporized at a substantially constant rate and wherein the composition of the vapor is substantially constant. The liquid odor-

ant in the vaporizing apparatus is constantly and automatically replenished from a reservoir so that the vaporization is continuous, and, furthermore, liquid odorant may be fed into the said reservoir 5 without interrupting odorization or disturbing the vapor phase balance.

Although the method and apparatus were designed for the purpose of making possible a proper and efficient use of an odorant having a wide 10 boiling range, it follows that it will also operate successfully with any liquid odorant. As an example of another odorant which we have used successfully we refer to "Pentalarm" having a boiling range of 130° F. to 200° F.

Referring more particularly to the drawings, 15 wherein like reference characters indicate like parts, the numeral 1 indicates an ordinary pipe line adapted to carry gas into which it is desired to introduce an odorant, the direction of flow 20 therein being indicated by an arrow. Pipes 2 and 3, provided with valves 2' and 3', connect the enclosed odorizing chamber with the pipe line 1, and a conventional restricting means 4, 25 preferably consisting of a disc having an orifice of reduced diameter, is placed in the pipe line 1 between the pipes 2 and 3. The restricting means 4 creates a pressure differential on either side thereof and causes a portion of the gas to flow from the pipe line 1, through the pipe 2 into 30 the enclosed odorizing chamber, and back to the pipe line 1 through the pipe 3. The amount of gas flowing through the odorizer may be regulated by an angle valve 4' provided in the pipe, 35 3. During its travel through the odorizing chamber this portion of the gas will become odorized, as will hereinafter be described, and after its return to the pipe line 1 it will mix with the remainder of the gas therein.

The odorizing apparatus consists, in part, of a 40 storage compartment or reservoir for the liquid odorant and a compartment into which the liquid odorant may overflow in the event that it is introduced into the apparatus at too rapid a rate. In the illustrative embodiment of the invention 45 shown in the drawings, these two compartments are contained within the cylindrical vessel 5, the storage compartment 6 being located above the overflow compartment 7 and separated therefrom by a partition 8 which may be substantially semi-spherical as shown.

The cylindrical vessel 5 may be supported in 50 upright position in any suitable way, as by means of a cylindrical support 9, and the overflow compartment 7 is provided at its lower end with an outlet pipe 10 extending through an aperture in said support and equipped with a valve 11.

The storage compartment 6 is provided at its 55 upper end with a supply pipe 12, equipped with a valve 13, and it is also provided at its upper end with a vent pipe 14 having thereon a valve 15. A gauge glass 16 is preferably connected to the storage compartment 6 by pipes 17 and 18 in the usual manner in order that the amount of liquid in the storage tank can be readily ascertained.

The overflow compartment 7 is provided adjacent its upper end with a relatively large aperture 19 (Figs. 3 and 4) and a cylindrical housing 20 is secured about the periphery of the aperture, as for example by welding, projecting laterally outwardly from the overflow compartment. The housing 20 is provided at its outer end with a flange 21 to which a header 22 is secured by means of bolts and nuts 23, 23.

A vessel 24, hereinafter referred to as the float 75 compartment, is secured to the header 22 and

projects inwardly therefrom within the housing 20. As shown, the bottom of the float compartment 24 is curved to conform roughly with the curvature of the housing 20 and the side walls 25, 25 are vertical. The header 22 forms one of the end walls of the float compartment, and the other end wall is shown at 26. An aperture 27 is preferably provided in one of the side walls 25 a short distance below its upper edge.

A relatively small compartment generally designated at 28, hereinafter referred to as the bubbling compartment, is secured to the end wall 26 of the float compartment 24 and lies within the upper portion of the overflow compartment. The bubbling compartment may be cylindrical as shown in the drawings, one end being closed by the vertical wall 29 and the other being partially closed by the end wall 26 of the float compartment 24, leaving an opening 30 through which gas may pass from the bubbling compartment to 20 the interior of the housing 20.

Liquid odorant passes from the storage compartment 6 to the float compartment 24 through a pipe 31, the liquid in the float compartment being maintained at the desired level (substantially that shown in the drawings) in a manner hereinafter described. The liquid odorant, passing through the aperture 32 in the end wall 26, will partially fill the bubbling compartment 28, and, obviously, the level of the liquid in the bubbling compartment will be the same as the level of the liquid in the float compartment.

The pipe 2, which, as stated above, supplies gas to the odorizing chamber, enters the header 22 and there communicates with a horizontal 35 conduit formed of two pipes joined at their ends by a conventional coupling 34. The conduit 33 extends inwardly to a point within the bubbling compartment 28, and at its inner end is provided with an elbow joint 35 which curves downwardly 40 and supports a short vertical pipe 36. The lower end of the pipe 36 is threaded into a disc 37 and the disc is provided with a peripheral skirt 38 extending downwardly and threaded at its lower end. A perforated cap 39 is threaded to the lower end of the skirt, and, as indicated in the drawings, the cap 39 is positioned slightly below the normal level of the liquid within the bubbling compartment 28.

It will now be apparent that the restricting means 4, which may be adjusted to create a pressure differential of from two to three pounds, will cause a portion of the gas on the upstream side to flow from the pipe line 1 through the pipe 2 and the conduit 33 and downwardly within the bubbling compartment 28 through the pipe 36, and thence into the liquid odorant in the bubbling compartment through the perforated cap 39. The gas will then pass upwardly through the liquid and out of the bubbling compartment 60 through the opening 30 and into the upper portion of the overflow compartment 7 by way of the aperture 19. The gas then passes out of the odorizing chamber and back into the main pipe line through the pipe 3 which is connected to the upper portion of the overflow compartment 7.

As the gas passes from the perforated cap 39 and bubbles up through the liquid odorant contained in the bubbling compartment, the liquid odorant will evaporate and the vapor therefrom 70 will mix with the gas. As the liquid evaporates, it is replaced by the flow of liquid from the storage tank 6 into the float compartment 24 and from the latter, through the aperture 32 into the bubbling compartment.

Although the gas may pass into the housing 20 and contact the surface of the liquid in the float compartment 24 during its passage through the odorizing apparatus, this will not occur until 5 after the gas has been substantially saturated with vapor in the bubbling compartment, and, therefore, there is very little evaporation of the liquid odorant in the float compartment.

At the start, there are certain fractions of 10 liquid odorant in the bubbling compartment which, due to large mol-fractions, or high vapor pressure, or both, evaporate more rapidly than the remainder of the associated components. This initial higher rate of vaporization results in 15 the lowering of the mol-fractions of these components thus leading to a resultant lowering of their rate of vaporization and a proportional increase in the rates of vaporization of the other components by reason of the increase in the mol- 20 fraction of the less volatile components.

Partly owing to the relatively small size of the 25 bubbling compartment in which the vaporization takes place, it will be found that very soon after the apparatus has been placed in operation, the relative quantities of the various components in the vapor will be equal to their relative quantities 30 in the original liquid or in other words, that the composition of the vapor is the same as the composition of the original liquid. Furthermore, the rate of evaporation quickly becomes constant.

As long as the conditions of gas flow through the apparatus do not vary, the vapor phase balance is maintained, or in other words, the rate of 35 evaporation of the liquid and the characteristics of the vapor remain constant. A change in the pressure or rate of flow of the gas will result in a temporary change in the rate of evaporation or in the proportions of the various components of the vapor but a new vapor phase balance will 40 quickly be obtained, and the input of liquid odorant will again exactly equal the output.

In order to quickly reach and maintain this vapor phase balance wherein the rate of evaporation and the composition of the vapor is constant, it is apparently necessary to use a relatively 45 small bubbling compartment and to contact the gas with the liquid only at the surface of the liquid, thus taking advantage of the fact that evaporation of a liquid in the presence of a gas is more rapid if the relative quantity of the liquid 50 is small. The dimensions of the bubbling compartment, and the depth of the outlet ports below the liquid therein are only great enough to insure that the gas will actually bubble through 55 the liquid and not force the liquid out of the compartment when flowing at a maximum rate.

The quantity of the liquid which is acted upon by the gas may be still further reduced by the provision of a plate 40, having a central aperture 46', transversing the bubbling compartment a short distance below the perforated plate 39.

Furthermore, it appears to be highly desirable, if not essential, to replenish the supply, in the 60 bubbling compartment, at or near the surface of the liquid and the aperture 32 is located accordingly.

To prevent the accumulation of heavier fractions of liquid in the bubbling compartment, we 65 have provided a pipe 41 which is connected at one end to the bottom of the bubbling compartment 29 and at the other end to the lower portion of the float compartment 24. Any heavier fractions which may tend to accumulate in the 70 bubbling compartment at commencement of op-

erations will flow off through the pipe 41 and will flow back into the float compartment.

The liquid odorant in the float compartment 24 and bubbling compartment 28 is normally maintained at the desired level by employing 5 what will be hereinafter referred to as the barometric feed principle. For this purpose a seal pipe 42 is provided comprising a pipe which extends from the top of the reservoir 6 to the header 22 where it connects with one end of a 10 pipe 43, the other end of the pipe 43 extending downwardly to a point below the level at which it is desired to maintain the liquid odorant. Communication between the interior of the apparatus and the outside atmosphere is shut off by closing 15 valves 13 and 15 after the reservoir 6 is partially filled with liquid. Sufficient liquid will flow into the float chamber 24 to cover the end of the pipe 43 and the outlet of the pipe 31 and the liquid will flow up the pipes 43 and 42 to the same level 20 as the liquid in the storage compartment 6. Hydrostatic equilibrium will thus be established, the initial levels of the liquid being determined by the pressures acting on the respective liquid surfaces and difference in the height of the liquid 25 surfaces.

In other words, the downward pressure per square inch on the liquid in the reservoir 6 will be equal to the downward pressure per square inch on the liquid in the float chamber 24 minus 30 the weight of a one-inch vertical column of liquid extending from the level of the liquid in the float chamber to the level of the liquid in the reservoir 6. It follows therefore that if liquid is taken from the compartment 24, in the absence of 35 changes in pressure, it will be replaced by additional liquid flowing from the reservoir 6 through the pipe 31 into the float chamber 24, and gas will bubble back into the space above the liquid in the reservoir. Hence, there will be no material variation 40 in the level of the liquid in the absence of sudden changes in pressure.

However, if there should be a sudden drop in the pressure of the gas within the housing 20 or if there should be a sudden increase in the pressure 45 of the gas acting on the liquid in the reservoir 6, the level of the liquid in the compartment 24 will rise very rapidly. To safeguard against this eventuality, we have provided a valve 44 actuated by a float 45 within the float compartment 24. The valve 44 and the height of the float 45 are so adjusted that the valve is normally open, but if a sudden and rapid flow of liquid into 50 the float compartment 24 should occur, the valve 44 will close and prevent the flow of further liquid 55 from the reservoir 6.

In the event that the float valve should fail to function or in the event that the seal pipe 42, which is not controlled by the float valve, contains a large amount of liquid, a sudden change 60 in pressure may cause the liquid in the float compartment 24 to overflow through the aperture 27, but the overflow will pass harmlessly from the housing 20 into the overflow compartment 7 and will not interfere with the operation of the 65 odorizing apparatus.

If an undesirably large amount of fluid should accumulate over a period of time in the overflow compartment 7, it may be drawn off through the pipe 10 by opening valve 11.

At any particular time, the amount of fluid in the storage compartment 6 may be ascertained by opening the valves 46 and 47 and permitting the fluid from the storage tank to enter the gauge glass 16 through the pipe 18.

In order to discover whether any liquid is flowing at any particular time from the storage compartment 6 to the float chamber 24, flow may be established directly from the gauge glass through a pipe 48, controlled by a valve 49 into the pipe 31. A valve 50 is provided in the pipe 31 between the storage compartment 6 and the junction of the pipe 48, and if this valve is closed, and there is any flow through the pipe 31, there will be a violent fluctuation of the level of the liquid in the gauge glass.

In order to replenish the supply of liquid in the storage compartment 6, the valves 49 and 50 are closed to temporarily stop the flow of liquid from the storage tank into the float chamber, and a valve 51, which is provided in the seal pipe 42, is closed to maintain the level of fluid in the seal pipe. The valves 13 and 15 in the supply pipe and vent pipe, respectively, are then opened, and liquid may be introduced through the supply pipe 12. The valves 13 and 14 are then closed before the valves 49, 50, and 51 are opened.

Since in normal operation the pressure on the surface of the liquid in reservoir 6 usually differs from atmospheric pressure, the normally existing hydrostatic equilibrium will be broken by opening either of the valves 13 or 15, but, after they are closed, equilibrium will quickly be restored, and by reason of the provision of the three different controls, mentioned above, (1) the barometric feed, (2) the float valve, and (3) the provision for overflow, this temporary disturbance does not interrupt and, in fact, has no substantial effect on the odorization of the gas.

The rate of evaporation of a given liquid odorant in a given apparatus of this type will depend upon the rate of flow of the gas through the bubbling compartment, and this, of course, depends upon the rate of flow of the gas in the main pipe 1.

Although the rate of evaporation is, to a slight extent, inversely proportional to the pressure of the gas in the pipe line, a vapor phase balance can quickly be obtained for any pressure condition. It will be noted that the rate of flow of the gas through the main and the odorizer

may differ widely under the same conditions of pressure. Consequently, the advantage of providing an odorizer which will supply the odorant in quantities proportional to the rate of flow of the gas will be apparent.

The apparatus does not require the attention of an operator except for an occasional inspection of the gauge glass and replenishment of fluid in the storage compartment. When the apparatus is decommissioned the fluid therein may be withdrawn through a valve 52 provided for this purpose in the float compartment.

It is obvious that many changes might be made in the apparatus without departing from the scope of the invention, and such modifications as will be obvious to those skilled in the art are to be regarded as within the purview of the invention.

We claim:

In apparatus for introducing an odorous vapor into a confined stream of inflammable gas, an elongated upright chamber having a partition intermediate its ends which divides the chamber into an upper compartment and a lower compartment, the upper compartment being adapted to hold a supply of volatile liquid, the lower compartment having an aperture in one side thereof and adjacent the said partition, a housing secured to the lower compartment at the aperture and extending outwardly therefrom, a header removably secured to and closing the end of said housing, a vessel secured to and supported by the inner wall of the header and extending inwardly therefrom, a conduit for conducting the volatile liquid from the upper compartment to the vessel, means for controlling the liquid level in the vessel, a conduit for conducting gas into contact with the liquid in the vessel, a passageway providing communication between the upper part of said vessel and the lower compartment, and an outlet for the gas, the vessel and the outlet being located a substantial distance above the bottom of the lower compartment whereby the latter acts as a receptacle for any liquid which may overflow from the vessel.

ROBERT M. HUTCHISON.
